UNITED STATES PATENT OFFICE.

WILLIAM LENDER, OF LOS ANGELES, CALIFORNIA.

AUTOMATIC RAILWAY-CROSSING.

1,255,617.

Specification of Letters Patent.

Patented Feb. 5, 1918.

Application filed August 24, 1916. Serial No. 116,625.

To all whom it may concern:

Be it known that I, WILLIAM LENDER, a citizen of the United States, and a resident of Los Angeles, in the county of Los Angeles and State of California, have invented new and useful Improvements in Automatic Railway-Crossings, of which the following is a specification.

My invention relates to improvements in automatic railroad crossings in which means are provided to eliminate the break, gap, or interruption of the rail necessary in common railroad crossings; and the objects of my invention are, to reduce the noise in such railroad crossings due to the jar of the wheels of a passing train over such gap or interruptions in the rails in the crossings; to provide a strong base to which the operating mechanism is secured; to provide rail expansion arresters, or spacers; to provide a crossing which allows a passing of a train at a very high speed; the invention consisting in the construction, combination and arrangement of devices hereafter more fully described and claimed, and illustrated in the accompanying drawing, in which—

Figure 1 is a top view of my device.

Fig. 2 is the top view of the operating mechanism.

Fig. 3 is a vertical section through the spider and the operating mechanism on line 3—3 of Fig. 1.

Fig. 4 is the top view of the turning rail-pivot.

Fig. 5 is a slight modification of the turning rail-pivot.

Fig. 6 is the side view of the turning rail-pivot.

Fig. 7 is the approach jar-arrester.

Fig. 8 is an end view of the rail clamp for the approach jar arresters.

Similar numbers refer to similar parts throughout the several views.

The base plate 1 is constructed to receive the rails 2, 3, 4, 5, 6, 7, 8 and 9. Rails 10, 11, 12 and 13 are formed on the base plate 1 alining with the first named rails. A strong support for the operating mechanism is formed in the four armed spider 14, being secured at its ends to the base plate 1. A vertical cross-section through the spider is shown in Fig. 3, a heavy center-pivot 15 being secured in the center of the spider, this being at the same time the center of the four rails, forming a crossing. The

center pivot projects downwardly and serves as a support for the operating disks 16.

A turning rail-pivot is vertically disposed in each junction of two rails as indicated at 17, 18, 19 and 20. Such rail-pivot consists of a short rail-block 21 formed on top of a supporting flange member 22, a stem 23 projecting downwardly from the supporting flange terminating in the pin 24. The rail-block 21 is shown in Fig. 4 as being formed off the center on the supporting flange 22, but it will easily be understood that the rail-block can be in the center of the supporting flange diagonally over the top of the flange member 22, as shown in the slightly modified construction in Fig. 5.

The reference characters 5, 8, 10 and 12 indicate that Fig. 4 illustrates the junction of those rails with the rail-pivot 19 filling the gap in this junction, see Figs. 1 and 2. A lever 25 is secured to the pin of each rail-pivot, see Fig. 2. The different levers are connected with the operating disks 16, by the connecting rods 26, 27, 28 and 29 respectively. Operating rods 30, 31, 32 and 33 are also connected to the operating disks 16.

A pulling on the rod 31 causes the disks 16 to turn around the pivot 15 in a right hand direction, the Fig. 2 illustrating the position which is obtained after such pulling. The pulling on the rod 33 causes a turning of the disks 16 in the same direction, this showing that the passing of a train in either direction on a certain track will cause the setting of the rail-pivots to align with the track on which the train is passing.

The passing train causes a pulling on the rods 30, 31, 32 and 33 by rushing against the lever 34 mounted between the rails of each track, see Fig. 1. The lever 34 is shown in Fig. 7 in detail, being secured to a shaft 35, the lower end 36 being connected to the operating rods. The shaft 35 is journaled in clamp bearings 37, detailed in Fig. 8. Levers of this kind are mounted between the tracks a suitable distance before each crossing. The operating of the levers mounted between the rails of the track running in one certain direction causes the levers between the rails crossing the first track to move back to the original position, ready to be operated on by a train coming on the crossing track, see Fig. 2, where the pulling on the operat-

ing rods 30 and 32 will cause the operating rods to move in the opposite direction as described above.

This automatic crossing allows a high speed to the crossing train as the rail-pivots are instantly put in alinement with the rails on the track on which the train is approaching. To reduce the jar, which will naturally be caused by a fast passing train, a jar arrester is inserted in each operating rod, detailed in Fig. 7. The operating rod end 42 in Fig. 7 terminates in a sleeve 39 which is provided with a longitudinal slot 40, and check nuts 41 on the end. A flat key 43 is inserted through the operating rod 33 fitting slidingly in the slot 40 of the sleeve. A washer 44 is placed before the key, and between the washer and the check nuts a spring 45 is placed to serve as a jar arrester. Below the supporting flange 22, of each rail-pivot, a rail expansion arrester 46 is placed of a slightly larger diameter than the supporting flange, so as to stop the expanding rail from touching the turning rail-pivot, which would perhaps prevent the rail-pivot from turning. To adjust the connecting rods, turn-buckles 47 are inserted, see Fig. 1.

It will easily be understood that this device can easily be operated from the switch

tower by connecting the necessary rods to the lever 34, and to the same lever it will also be easy to connect signals to show to the engineer of an approaching train how the crossing stands.

The whole device will be mounted on a strong concrete foundation, and as all mechanism is rigidly connected to the base, the automatic operation of this device is positive.

Having thus described my invention, I claim:

A railway crossing of the type described consisting of rail pivots turnably mounted in each intersection of the rails, operating means attached to the rail pivots, jar arresting means inserted into the operating means having stops making the movement of the operating means positive yieldingly, and an operating lever mounted between the rails extending upwardly for oscillating movement in the path of a passing train to be operated by the train.

In testimony whereof I hereunto affix my signature in the presence of two witnesses.

WILLIAM LENDER.
